UNITED STATES PATENT OFFICE.

THOMAS M. TOLLIVER, OF WASHINGTON, DISTRICT OF COLUMBIA.

OVERFLOW-ALARM FOR REFRIGERATORS.

1,122,667.

Specification of Letters Patent.

Patented Dec. 29, 1914.

Application filed January 7, 1914. Serial No. 810,710.

To all whom it may concern:

Be it known that I, THOMAS M. TOLLIVER, a citizen of the United States, residing at Washington, District of Columbia, have invented certain new and useful Improvements in Overflow-Alarms for Refrigerators; and I hereby declare the following to be a full, clear, and exact description of the invention, such as will enable others skilled in the art to which it appertains to make and use the same.

This invention relates to overflow alarms for refrigerators and has for an object to provide a float control electric circuit closer that will be easily and quickly detachable to cleanse or replace a fouled or water logged float.

A further object is to provide a device of this character in which the float is carried by a resilient arm that is swingably secured in place by a single screw, the resiliency of the arm coacting with the screw in attaching one of the circuit wires to the arm.

A still further object of the invention is to provide a device of this character which will be extremely simple in construction, consisting of a few parts that will not easily get out of order, and which may be manufactured at a minimum cost.

With the above objects in view, the invention resides more specifically in the resilient float carrying arm in combination with the securing screw whereby the screw is enabled to perform the dual function of a binding post for one circuit wire and a means for removably attaching the float in place, it being understood that various changes in the minor details of construction may be resorted to within the scope of the appended claims.

In the accompanying drawing, Figure 1 is a fragmentary front elevation showing the application of my invention, and Fig. 2 is a detailed sectional view showing parts of the invention.

Referring now to the drawing in which like characters of reference designate corresponding parts in the various views, 10 designates an ordinary refrigerator, and 11 the drip pan thereof. In carrying out my invention I provide a battery cell 12, a buzzer or electric bell 13, electric circuit wires 14 and 15, and a float controlled electric circuit closer 16 which serves to close the circuit and actuate the bell or other alarm when the water in the drip pan reaches a prede-

termined height. The battery cell, circuit wires and alarm device may be located at any desired place while the circuit closer is attached to the bottom of the refrigerator.

In constructing the circuit closer I employ a base plate 18 that is equipped with attaching screws 19 or the like and carries centrally an insulated contact 20 to which is fixably secured in any preferred manner the circuit wire 14.

An arcuate resilient arm 21, formed of metal, is pivotally attached to the ends of the base plate, as will be hereinafter more fully described, and centrally carries a vertically movable float stem 22 which is equipped below the arm with a float 23, which may be of cork if desired to promote cheapness, the stem being equipped above the arm with a nut 24 to limit downward movement of the stem and to prevent the same dropping from the arm. The arm is equipped at one end with an integral gudgeon 25 which enters an orifice 26 in one end of the base plate, and is equipped at the opposite end with an opening 27 which loosely receives a set screw 28 that is screwed into the adjacent end of the base plate as shown at 29, the arm rocking on its gudgeon and set screw to facilitate the float swinging over the rim of the drip pan upon withdrawal and replacing of the same.

A washer 30 is placed on the set screw next to the end of the base plate and the bared end of the circuit wire 15 is wrapped about the set screw and is held clamped against the washer by the end of the resilient arm 21 whereby a good electrical connection is made, the set screw 28 thus forming means for removably securing the arm 21 in place and being assisted by the resiliency of the latter in performing the function of a binding post for the circuit wire 15.

A frequent annoyance met with in devices of this character is that the floats become fouled from foreign matter in the drip water and from age become water logged, thus impairing the proper action of the device. When it is desired to quickly remove the float for cleansing or renewal, it is simply necessary to remove the single set screw 28 whereupon the arm 21 may be easily withdrawn from the base plate and the cleansing or renewal of the float conveniently accomplished.

In operation, the float is raised upwardly by the water in the drip pan until the water

reaches a predetermined height where upon the float stem, which is of metal, contacts with the contact of 20 and closes the circuit at this point with a resultant sounding of the alarm to give warning that the drip pan is about to overflow.

What is claimed is:

1. In a float controlled electric alarm device, a circuit closer comprising an attaching member, a resilient yoke, a float carried by said yoke, a gudgeon at one end of said yoke engaging said member, a removable set screw at the other end of said yoke engaging said member and coacting with said gudgeon in hinging said yoke on said member, and a circuit wire clamped by the resiliency of said yoke on said screw.

2. In an electric alarm device, a circuit closer comprising an attaching member, a contact carried by said member, a resilient yoke, a movable contact carried by said yoke engageable with the first named contact, a gudgeon at one end of said yoke, a set screw at the other end of said yoke, said gudgeon and said set screw coacting in removably securing said yoke to said member, and a

circuit wire clamped by the resiliency of said yoke on said screw.

3. The combination with a refrigerator, a drip pan thereunder, and an electric signal device, of an attaching member on the refrigerator bottom, a stationary contact carried by said member, a resilient electrical conductor yoke, a buoyant electrical conductor contact slidably carried by said yoke and extending into said pan and adapted to engage said stationary contact, a gudgeon at one end of said yoke engaging said member, a set screw at the other end of said yoke engaging said member and coacting with said gudgeon in removably hinging said yoke on said member, a circuit wire clamped by the resiliency of said yoke on said screw, a circuit wire connected to said stationary contact, and a source of electricity connecting said wires and said alarm device.

In testimony whereof, I affix my signature, in the presence of two witnesses.

THOMAS M. TOLLIVER.

Witnesses:

FRANCIS BOYLE,

Mrs. V. B. TOLLIVER.
